LIGHTING FIXTURE

Emanuel Allan Rothman, Brooklyn, N. Y., assignor to McPhilben Manufacturing Co., Inc., Brooklyn, N. Y., a corporation of New York

Application July 23, 1956, Serial No. 42,343

Term of patent 14 years

(Cl. D48—4)

FIG. 3.

FIG. 4.

FIG. 1.

FIG. 2.

Fig. 1 is a front view of a lighting fixture, showing my new design.

Fig. 2 is a side view thereof.

Fig. 3 is a top view thereof.

Fig. 4 is a sectional view taken along line 4—4 of Fig. 1, part being broken away for clarity.

I claim:

The ornamental design for a lighting fixture, substantially as shown.
